Des. 227,564
Patented July 3, 1973

227,564

FISH BAIT HOLDER

Charles P. Ritter, 704 E. Prairie Ronde,
Dowagiac, Mich. 49047

Filed Aug. 13, 1970, Ser. No. 24,475

Term of patent 14 years

Int. Cl. D22—05

U.S. Cl. D22—31

FIG. 1

FIG. 2

FIG. 3

FIG. 1 is a perspective view of a fish bait holder embodying the present design;

FIG. 2 is another perspective view of the holder shown in FIG. 1, the view being taken from the opposite side of the holder; and

FIG. 3 is an exploded perspective view.

I claim:

The ornamental design for a fish bait holder, as shown.
